UNITED STATES PATENT OFFICE.

AMENZO GRIFFITH, OF SPRINGFIELD, MASSACHUSETTS.

MACHINE FOR STUFFING MATTRESSES.

SPECIFICATION forming part of Letters Patent No. 591,077, dated October 5, 1897.

Application filed May 21, 1897. Serial No. 637,549. (No model.)

To all whom it may concern:

Be it known that I, AMENZO GRIFFITH, a citizen of the United States, and a resident of Springfield, in the county of Hampden and State of Massachusetts, have invented certain new and useful Improvements in Machines for Stuffing Mattresses, of which the following is a specification.

This invention relates to improvements in machines for stuffing mattresses of the class in which there is comprised a broad shallow box or receiver having a movable cover or covers, a movable gate closing one end of the box and separating it from a spout, and a stuffing-bar and means for imparting thereto a motion in the direction of the length of the box for expelling the compressed excelsior or other mattress-filling material, the same being also adapted to be withdrawn in a reversed direction after its forward thrust.

The present invention relates to improved combinations of parts comprised in a mattress-stuffing machine such as has been above in a general way referred to; and the invention consists in constructions and combinations or arrangements of parts, all substantially as will hereinafter fully appear, and be set forth in the claims, all to the end of simplifying the machine and cheapening and rendering the same more satisfactory and available and increasing its capability for rapidly performing its required work.

My improved mattress-stuffing machine is illustrated in the accompanying drawings, in which—

Figure 1 is a central sectional elevation taken lengthwise of the machine. Fig. 2 is a plan view of the machine.

Similar letters and figures of reference indicate corresponding parts in both of the views.

In the drawings, A represents the frame of the machine, comprising opposite posts or standards 10, 10, the paired separated top rails 12 and 13, the bed a, forming the bottom of the stuffing-box E, supported by and connecting the opposite pairs of the rails above their lower ends, and suitable cross ties or bars, as 14, 15.

B and C represent the divided movable cover-sections of the mattress-stuffing box E, the said sections or members being pivoted to the frame, as seen at 16 and 17, and are

operated by novel means, which will be hereinafter particularly referred to.

One end of the mattress-stuffing box is closed by the movable gate b, this gate dividing the chamber comprised within the stuffing-box from the spout d, on which latter the open mouth of the mattress-tick is drawn and held to receive the filling after the same has been formed and compressed in the stuffing-box, principally by covers B, C, and to some extent by the bar D, which is supported by the movable frame f, which latter is connected with the endless chain g, that runs around the sprocket-wheels h, h, one of these wheels being carried on a shaft 20, provided with the gear-wheel 22, which is in mesh with the pinion-wheel 23 on the driving-shaft 24, which shaft has thereon the three pulleys i, i², and i³, two being loose and the other one fixed on the driving-shaft.

An open belt and a cross-belt are provided, as indicated at j, j², Fig. 1, which may run on the loose pulleys, either one thereof being adapted to be shifted onto the fixed pulley i² at one time, so as to give a running motion to the chains g (duplicated) in either direction desired, which chains have, as seen at 25, a connection with the frame f, on which the stuffing-bar D is supported and in unison with which said stuffing-bar moves.

The space and boundaries between the lower and upper sides of the horizontal rails 12, 13 of the frame A constitute ways for the bars G, mounted therein for longitudinal slide, both of said bars at one end being united by the cross rod or shaft k, on which, next to the extremities of the bars G, are journaled the flanged rollers m, m, which run along the upper side of the horizontal rail 13, serving as trucks for the said bars G. Each of the said rails 13 has within its upper side a longitudinal groove 30, in which a stud, rib, or projection 32, extended below the under side 95 of the bar G, has a sliding fit.

The paired bars H, H are pivotally hung opposite each other from the aforesaid cross rod or shaft k, which unites the pair of bars G, the lower ends of these depending bars H being pivoted, as indicated at 33, to the cross-cleat 34, which is affixed to the upper side of the section B of the cover.

A sprocket-chain J, which has its one end

35 affixed or anchored to the cross-rod k , extends from this connection around the sprocket-wheel n , which is on the cross-shaft o , supported horizontally in journals 37 37 at 5 the right-hand upper corner of the frame, this chain thence continuing in an oblique direction downwardly to a connection, as seen at 39, with the cross-cleat 40, which is affixed to the upper side of the cover-section near 10 its edge, which meets the edge of the cover-section B.

The reciprocatory movement is imparted to the paired bars G G by means as follows: Paired sprocket-wheels p are affixed at the 15 ends of the shaft o , and paired sprocket-wheels q are also affixed at the opposite ends of the cross-shaft r at the top of the machine near the end of the latter, opposite that at which the shaft o is mounted, and the duplicated 20 sprocket-chains s run around said sprocket-wheels p q , each of these chains being affixed, as seen at 42, to the bar G. The shaft r has thereon the gear-wheel t , in mesh with which is the pinion u on the shaft v , which has 25 thereon the two loose pulleys e e^2 , one of which is driven in one direction by the open belt e^3 , while the other is driven in the opposite direction by the cross-belt e^4 , which belts are understood as driven from a pulley on any 30 suitable or available overhead power-driven shaft. Each of these pulleys e e^2 has on its hub a clutch member e^5 , and a coacting double clutch member w is splined on the shaft v and may be thrown into clutch with either 35 of the pulleys e or e^2 , whereby the shaft v may be rotated in either direction and the chains s caused to have a corresponding travel longitudinally forward or backward and the said bars G G therewith.

40 x represents a slide-rod supported in guide-supports for movement crosswise of the machine and having engaged therewith the pivoted lever x^2 , and this cross-rod carries the fixed arm x^3 , which engages in the groove 45 in the double clutch member w , all whereby by proper manipulation of said lever x^2 the shaft may be out of clutch or in clutch at one time with either of the pulleys e e^2 to be driven in the one or the other direction to 50 insure the proper travel of the bars G G, as desired.

Now, of course, it will be plain that with the cover-sections B C down and the parts correspondingly in the positions shown in the drawings and the clutches operated to rotate the shaft v to cause the chains s to move the bars G G to the left the chain J will be so drawn upon as to cause the cover-section C to be swung up in the nearly-upright position indicated by C², and the bars H H, having positive pivotal connections with both the rod k , which is bodily movable leftward, and also with the cleat 34 of the pivoted cover-section B, will, simultaneously with the elevation of 60 the cover-section C, effect the placing of the cover-section B in the nearly-upright position indicated by the dotted line B².

It will be apparent from the construction and operativeness of the various contrivances here illustrated that the mechanism at the top of the machine may be operated to elevate the cover-section, and while the clutch w is thrown out the mattress-filling may be placed and heaped up in the box, and then the clutch w is thrown into the other adjacent 75 pulley, (opposite the one which was in clutch when the covers were raised,) whereupon the covers will be lowered, and as the bars H H assume their vertical position they act as toggles or compression-bars to force the covers 80 into a horizontal position and suitably compress the mattress-filling material. When the covers are in their horizontal positions, the clutch is again thrown out, and the bar G has its endwise traveling movement im- 85 parted thereto through the pulleys and gearing described, it ejecting the compressed filling through the spout into the mattress, the gate having been slid from its closing position, and then the belts j and j^2 are shifted to cause 90 the stuffing-bar D to be moved to its original position, whereupon the mechanism at the top of the machine is again operated to effect the elevation of the cover-sections to permit the introduction into the box of another quantity 95 of the stuffing material, when the operations are repeated as before.

Having thus described my invention, what I claim, and desire to secure by Letters Patent, is—

1. In a mattress-stuffing machine, the combination with a stuffing-box and two hinged cover-sections therefor, of a bar and supports on which the same is mounted to move, wheels p q and chains or like flexible appliances running around said wheels and having a connection with said bar, means for imparting rotary movements to one of said wheels, a supporting and guiding wheel n , a chain or like flexible connection secured to said bar, running around said wheel n and connected to one of the cover-sections, and the bar H pivotally sustained by the said movable bar and pivotally connected to the other cover-section, substantially as described.

2. In a mattress-stuffing machine, the combination with a stuffing-box and two hinged cover-sections therefor, of the paired bars G G united by the cross-rod and supports on which the said bars are mounted to move, 120 wheels p q and chains or like flexible appliances running around said wheels and having connections with said bars, means for imparting rotary movements to one of said wheels, a supporting and guiding wheel n , a 125 chain or like flexible connection connected to said bar running around said wheel n and connected to one of the cover-sections and the bars H pivotally hung on said rod which is sustained by said movable bars, and having their lower ends pivotally connected to the other cover-section, substantially as described.

3. In a mattress-stuffing machine, the com-

- bination with a stuffing-box and two hinged cover-sections therefor and the rails 12, 13, the latter having the longitudinal groove, of the paired bars G G having the wheels *m m*, 5 united by the cross-rod and the projections 32, wheels *p q* and chains or like flexible appliances running around said wheels and having a connection with said bar, means for imparting rotary movements to one of said 10 wheels, a supporting and guide wheel *n*, a chain or like flexible connection connected to said bar running around said wheel *n* and connected to one of the cover-sections and the bars H pivotally hung on said rod which 15 is sustained by said movable bars, having their lower ends pivotally connected to the other cover-section, the spout, gate and reciprocating ejector-bar D substantially as described.
- 20 4. In a mattress-stuffing machine, the combination with the stuffing-box having the hinged cover-sections and the horizontal guideways, of the bars G G movably mounted on said guideways and having connections 25 with the cover-sections whereby, as they are moved, said sections will be opened and closed, wheels *p q* and chains or like flexible appliances running around them and connected to said bars G, and mechanism for imparting at 30 pleasure forward or rearward rotary movement to said wheels *q*, substantially as and for the purposes set forth.
5. In a mattress-stuffing machine, the combination with the stuffing-box having the hinged cover-sections and the horizontal guideways, of the bars G G movably mounted on said guideways and having connections 35 with the cover-sections whereby, as they are moved, said sections will be opened and closed, 40 wheels *p q* and chains or like appliances run-

ning around them and connected to said bars G, a gear *t* connected to move in unison with the wheels *q*, a shaft *v* having two, reversely driven, pulleys, loose thereon, and a fixed pinion *u* in mesh with gear-wheel *t*, a clutch 45 to place either of said reversely-driven pulleys in driving connection with shaft *v* and means for operating the clutch, substantially as described.

6. In a mattress-stuffing machine, in combination, the stuffing-box having the spout *d*, gate *b*, reciprocating bar D, and means for imparting its movement thereto, and the hinged cover-sections B D, the horizontal separated rails 12, 13 constituting guideways, 55 the bars G G movable in said guideways and united by the cross-shaft *k*, the shafts *o* and *r*, the former having the sprocket-wheels *n* and *p*, and the latter having the sprocket-wheels *q* and the gear-wheel *t*, the sprocket-chains *s s* running around the sprocket-wheels *p q*, and connected to said bars G, the chain *J* connected to the shaft *k* which is sustained by said bars, and running around sprocket-wheel *n* and connected to one of the covers 60 near its edge, the bars H H hung on said rod *k* and pivoted to the other cover-section, shaft *v* having pinion *u* and reversely-driven loose pulleys *e e* and having the clutch member *w*, the slide-rod *x* having the arm which engages 65 clutch *w*, and the lever *x* for operating said rod *x*, all substantially as described and for the purposes set forth.

In testimony that I claim the foregoing as my invention I have signed my name in presence of two witnesses.

AMENZO GRIFFITH.
